PAPER BREAK CONTROL DEVICE

Frederic E. Howdle, Milwaukee, and Theodore B. Jochem, Wauwatosa, Wis., assignors to Cutler-Hammer, Inc., Milwaukee, Wis., a corporation of Delaware

Application October 14, 1950, Serial No. 190,117

13 Claims. (Cl. 200—61.18)

1

This invention relates to control devices and more particularly to paper break control devices for use in connection with machines which embody or operate upon a traveling web, as for example a web press.

A primary object of this invention is to provide an improved paper break control device of the multiple web engaging shoe type for use with web presses handling a single wide web or a plurality of parallel running narrower webs, which upon breakage of a web or part thereof functions to afford stopping of the web press.

Another object is to provide a device of the aforementioned character having a single electric switch which is operable to afford stopping of the web press by response to web breakage by any one of its web engaging shoes.

Another object is to provide a device of the aforementioned character wherein the web engaging shoes are adjustable to various positions across the travel path of the webs.

A further object of the invention is to provide a device of the aforementioned character wherein each web engaging shoe can be individually positioned out of operating relation to the traveling web, or all such web engaging shoes can be brought into, and locked out of such operating relation simultaneously.

A still further object is to provide a device of the aforementioned character which may be readily adjusted within wide limits to various planes of web travel in the press.

Other objects and advantages of the invention will hereinafter appear.

The accompanying drawings illustrate a preferred embodiment of the invention which will now be described, it being understood that the embodiment illustrated is susceptible of various modifications in respect of its details without departing from the scope of the appended claims.

In the drawings:

Figure 1 is a somewhat schematic view in front elevation of the paper break control device in mounted relation to the side frames of a web press;

Fig. 2 is a view in front elevation of a right hand portion of the control device shown in Fig. 1;

Fig. 3 is a view in vertical section taken along the line 3—3 of Fig. 2;

Fig. 4 is a view in vertical section taken along the line 4—4 of Fig. 2;

Fig. 5 is a view, partially in section, of a left hand portion of the control device shown in Fig. 1;

2

Fig. 6 is a view in vertical section taken along the line 6—6 of Fig. 1, and

Fig. 7 is a fragmentary view in top plan of elements shown in Fig. 6.

5 The paper break control device, as depicted in Fig. 1, is designed for mounting between the side frames 10 and 11 of a web press. Generally considered, the control device includes as its major components web engaging shoe assemblies A, B, C and D, supporting shafts 12 and 13, a housing 14, a bearing housing 15, bearing bracket 16, a counterweight assembly 17 and a lock-up lever assembly 18.

Housing 14, as best shown in Figs. 2 and 4, is 15 preferably a built up structure having an end flange 14^a abutting against side frame 11 to which it is attached by a plurality of bolts 19. A cover plate 14^b removably secured, as by a plurality of bolts, to the top and bottom side portions 14^c and 20 14^d of the housing provides for access into the interior of the housing. The end portion 14^c of the housing is provided with a large circular opening within which fits the complementally formed portion 20^a of a circular bearing plate 20.

25 Bearing plate 20 is provided with a circular portion 20^b of larger diameter than portion 20^a, which is adapted to overlie and bear against the outer surface of portion 14^c of housing 14 adjacent said opening. Portion 20^b is provided with a plurality of bolt receiving openings 20^c which lie adjacent to and are spaced equidistant about its peripheral edge; the openings 20^c preferably being spaced from one another at rotary angles of 30°. The outer surface of portion 14^c of housing 30 35 14 is provided with six threaded openings 14^f. The openings 14^f are arranged in groups of three on opposite sides of the aforementioned large opening in portion 14^c and the openings in each group are spaced from each other at rotary angles of 10° along a circular arc concentric with that along which the openings 20^c in plate 20 are arranged. A pair of bolts 21 penetrating openings 20^c and taking into aligned openings 14^f secure plate 20 to housing 14.

40 45 As best shown in Fig. 2, plate 23 is provided with a circular recess opening to the outer surface of portion 20^b and communicating with the interior of housing 14 through an opening 20^d of smaller diameter formed in the portion 20^a.

50 A ball bearing 22 is adapted to seat within the aforementioned recess and is held in place by an annular plate 23 which is secured to the outer surface of portion 20^b. The inner race of bearing 22 is provided with a central opening to accommodate with a pressed fit the complementally

formed cylindrical portion 24^a of a stub shaft 24. Shaft 24 is also provided with a cylindrical portion 24^b of smaller diameter which extends through opening 20^a into the interior of housing 14.

As best shown in Figs. 2 and 3, a disc cam 25 is mounted on and rigidly secured to portion 24^b of shaft 24 by a pin 26. The peripheral edge of cam 25 is provided with a circular cam surface 25^a and a cam notch 25^b. A self-contained electric switch 27, which is rigidly secured to portion 20^a of plate 20 and lies within housing 14, is provided with an operating member 27^a which is normally biased to an outer extreme position relative to the switch housing and which has a roller follower 27^b on the end thereof adapted to engage cam 25 on the surface 25^a or in the notch 25^b thereof.

As best shown in Fig. 2, shaft 12, which in vertical cross section is of hollow square formation, fits adjacent one end thereof over the square portion 24^c of stub shaft 24 and is secured to the latter by screws 28 which penetrate receiving openings in a lever plate 29 and take into aligned threaded recesses formed in portion 24^c of shaft 24. Plate 29 is provided with an integral boss 29^a, which is square in vertical cross section and which projects at a right angle from the portion 29^b. Shaft 13, which like shaft 12 is preferably of hollow square formation in vertical cross section, fits over boss 29^a of plate 29 and is secured thereto by screws 30 which penetrate receiving openings in a channel bracket 31 and take into threaded recesses formed in a guide block 32 positioned against shaft 12 on the opposite side of the latter from bracket 31.

As best shown in Fig. 5, bearing bracket 16 is provided with a flanged base 16^a, through which project a plurality of bolts 33 which take into threaded recesses in side frame 10 for rigidly securing bracket 16 to the side frame. Bracket 16 is also provided with a cylindrical sleeve 18^b within which fits a cylindrical stub shaft 34. Stub shaft 34 is secured against rotation and axial movement in sleeve 18^b by a pair of set screws 35, and shaft 34 fits within a recess in bearing housing 15 wherein it is rigidly secured as by welding. Bearing housing 15 is provided with another recess to accommodate a ball bearing 36 which is held in place in such housing by an annular plate 37 secured to an outer surface of the housing 15. The inner race of bearing 36 is provided with a central opening extending therethrough to accommodate with a pressed fit the complementally formed cylindrical portion (not shown) of a stub shaft 38, which also has a square portion 38^a which fits within shaft 12. Shaft 38 is secured to shaft 12 by screws 39 which penetrate receiving openings in the latter shaft and take into aligned threaded recesses in the former shaft. Bearing housing 15 is also provided with a circular opening extending therethrough within which fits the cylindrical portion 40^a of a stub shaft 40 which is welded in place in housing 15. Shaft 40 is provided with a portion 40^b of square form in vertical cross section which fits within shaft 13 and which is secured to the latter by screws 41 in the manner aforescribed in connection with shafts 12 and 38.

In view of the foregoing it will be appreciated that shaft 12 is rotatable relative to bearing housing 15 and plate 20, whereas shaft 13 is non-rotatable with respect thereto. As will be hereafter more fully explained, the assembly com-

prising stub shaft 34, bearing housing 15, shafts 12 and 13, and plate 20 may be positioned in any of thirty-one different angularly spaced fixed positions in housing 14 and bearing bracket 16.

The details of the web engaging shoe assemblies A, B, C and D are best shown in Figs. 2, 6 and 7. Each such assembly includes a web engaging shoe 42, of the form best shown in Fig. 6, which is removably secured to a U-shaped member 43 which straddles and is rigidly secured to the outer race of a ball bearing 44. The inner race of bearing 44 is provided with a square central opening extending therethrough to afford mounting on shaft 12 so that the bearing is slideable longitudinally on shaft 12. Associated with each of the ball bearings 44 and web engaging arms 42 is a slider block 45 mounted on shaft 13. Each block 45 is provided with upwardly extending parallel side portions 45^a and 45^b which are disposed on opposite sides of the outer race of a bearing 44, a downwardly and outwardly extending portion 45^c and a substantially horizontally extending portion 45^d. The blocks 45 are provided with a square opening extending therethrough to accommodate shaft 13 and are split, as shown in Fig. 6, so that by loosening and tightening of bolts 46, the position of each such block can be changed as desired along the length of shaft 13. It will be appreciated that the assembly comprising a ball bearing 44 and a web engaging arm 42 will be shifted simultaneously along shaft 12 when its associated slide block 45 is shifted to a new position on shaft 13.

As best shown in Figs. 6 and 7, a fork-shaped member 47 is rigidly secured to and straddles the outer race of each of the bearings 44. When an associated web engaging shoe 42 is rotated to the broken line position designated I in Fig. 6, then a latch tip 47^a of its associated member 47 is adapted to engage within a rectangular opening 48^a formed in an L-shaped latch catch 48 which is mounted on a flat strip member 49 formed of spring steel. Member 49 is secured to the upper surface of slider block 45 between the portions 45^a and 45^b thereof, by screws 50 penetrating receiving openings in a flat rigid plate 51 overlying member 49, and in the latter, and taking into threaded recesses formed in the surface 45^c of slider block 45.

When a member 47 is latched in engagement with a latch catch 48 as aforescribed, its associated web engaging shoe 42 will be retained latched-up in position I. Unlatching of member 47 is readily accomplished by depressing latch catch 48 downwardly toward the portion 45^a of slider block 45, thereby disengaging latch tip 47^a from catch 48.

Coiled tension springs 52 which are each secured at one end thereof to a member 43 and at their other ends to adjustable eyelet screws 53, which respectively take into portions 45^c of the slider blocks 45, serve to bias associated web engaging shoes 42 for rotary movement into the broken line position designated IV in Fig. 6.

Straddling the outer and inner races, and secured to the inner race of each of the bearings 44 is a U-shaped member 54. When all of the web engaging shoes 42 are in the full line web engaging position designated III in Fig. 6 then shaft 12 will assume the position shown in Figs. 4 and 6. If the web W should break under any of the arms 42, the latter and the outer race of its associated ball bearing 44 will rotate anti-clockwise, as viewed in Fig. 6, and its associated member 47 rotating therewith ultimately engages

with an associated member 54 and thereafter the inner race of a bearing 44 and shaft 12 are caused to rotate in the anticlockwise direction. Cam 25 is thus caused to rotate anticlockwise so that the roller follower 27^b of switch 27 will then aline with the broken radial line designated IV in Fig. 3 within notch 25^b of cam 25, thereby effecting change in the circuit controlling position of switch 27, such as will afford stopping of the web press. After such operation shoe 42 will assume the position designated as IV in Fig. 6.

As will be appreciated, it is only required that one such web engaging shoe 42 respond to breakage of a web on which it bears in order to effect the aforescribed anticlockwise rotation of shaft 12 and operation of switch 27. In the event the other web engaging shoes are latched-up in position I, or are bearing on unbroken portions of the same or parallel running webs, the aforesigned anticlockwise rotation of shaft 12 will in nowise disturb the positions of the other web engaging shoes. The aforesigned individual ball bearing mounting of each web engaging shoe on shaft 12 permits rotation of the latter relative to those shoes which are then bearing on webs or latched-up out of engagement with such webs.

Following dropping of a web engaging shoe 42 to position IV, shown in Fig. 6, in response to web breakage, return of the same to web engaging position III is effected by manually moving the same into the latter position. It will be seen that upon moving such a shoe 42 from position IV to III that member 47 moves out of engagement from member 54, and if it were not for counterweight assembly 17, which will now be described in detail, it would be necessary to separately rotate shaft 12 back to its position depicted in Figs. 4 and 6.

As is best shown in Figs. 2 and 4, counterweight assembly 17 comprises an annular plate 55 having a square opening formed therein to accommodate shaft 12 on which it is mounted. Plate 55 is restrained against movement longitudinally on shaft 12 by screws 56 which take into threaded openings in shaft 12 on opposite sides of the plate. Plate 55 is provided with a plurality of openings 55^a formed therein which are spaced at equal rotary angles of 30° about its periphery adjacent its peripheral edge. A substantially rectangular weight 57 having an arcuate slot formed in one end thereof which is slightly greater in width than the width of plate 55 to accommodate the latter therewithin, straddles plate 55 and is secured to the latter by a bolt 58 penetrating aligned openings in weight 57 and an opening 55^a of plate 55. For the plane of travel of the web W depicted in Fig. 6, weight 57 would preferably be positioned and secured to plate 55 as shown in Fig. 4. Weight 57 serves to partially counterbalance the bias of any one of the springs 52 of the web engaging shoe assemblies A, B, C and D. Then when all of the web engaging shoes 42 which might be in position IV are returned from such position to normal web engaging position III, shaft 12 will return to its position depicted in Figs. 4 and 6 under the influence of weight 57, thereby eliminating need for separately returning shaft 12 to such position.

As aforesigned, each of the web engaging shoes 42 of the web engaging shoe assemblies A, B, C and D can individually be latched up in the position I depicted in Fig. 6, in which position they would be out of bearing engagement with the web W, if the latter is in the plane depicted in Fig. 6. It might be desired to latch up certain 75

thereof when a single or a plurality of narrow webs are run through the press requiring less than the number of web engaging shoes available.

5 It is also a feature of the present invention that such of the web engaging shoes 42 as are not in the individual latched-up position I can be locked-up out of working relation to traveling webs simultaneously in the broken line position designated II in Fig. 6, in which position shaft 12 would assume such a position that cam 25 would be rotated clockwise to a position where roller follower 27^b of switch 27 alines with the broken radial line designated II in Fig. 3. Such 10 simultaneous lock-up is afforded by lock-up lever assembly 18 which will now be described in detail.

As best shown in Figs. 2 and 4, lock-up lever assembly 18 comprises the aforementioned guide block 32 which is secured to shaft 13 on the opposite side from channel bracket 31. Guide block 32 is provided with a circular opening 32^a extending lengthwise therethrough to accommodate with a free fit the cylindrical shaft 59^a of lock-up lever 59. Guide block 32 is also provided 15 with guide slots 32^b and 32^c, disposed on opposite sides of and merging with opening 32^a, and which extend from the upper end of the block to a point substantially midway between the opposite ends of the block. Lever 59 is provided 20 with a pin 59^b extending transversely of its shaft 59^a, which pin is adapted to move in the guide slots 32^b and 32^c of block 32. A coiled compression spring 60, which is disposed about shaft 59^a of lever 59 below the bottom end of block 32, 25 bears at one end against the bottom surface of block 32 and at its other end against a flange 59^c on shaft 59^a of lever 59. Spring 60 normally biases lever 59 to a downward extreme position in block 32, which position is attained when the 30 guide pin 59^b abuts against the bottom ends of the slots 32^b and 32^c in block 32. Lever 59 is provided with a substantially spherically shaped handle 59^d which is non-rotatably secured to the lower end of shaft 59^a. At its upper end, 35 shaft 59^a is preferably provided with a hemispherically shaped tip. Block 32 at its upper end is provided with shallow notches 32^d disposed on opposite sides of opening 32^a and at rotary angles of 90° with respect to the slots 32^b and 32^c.

40 When lever 59 is pushed upwardly within block 32, the upper end of shaft 59^a will ultimately engage with lever plate 29 on that portion of the latter depending to the left hand side of shaft 12 as viewed in Fig. 4. Further upward movement of lever 59 will thereafter effect clockwise movement of shaft 12, and consequently the members 54 of the respective web engaging shoe assemblies will engage with their associated members 47 to effect clockwise movement of the web engaging shoes 42 to position II. By the time the web engaging shoes 42 have been moved to the last mentioned position, the pin 59^b of lever 59 will have moved upwardly clear of the upper end of guide block 32 and then the shoes 45 may be locked-up in such position by rotating lever 59 until the pin 59^b comes to rest within the notches 32^d in block 32. Each of the shoes 42, as are not in the individual latch-up position II, will be released from such locked-up position II, simultaneously, by rotating shaft 59^a of lever 59 until the pin 59^b is alined with notches 32^b and 32^c in block 32 and then releasing lever 59 for downward movement in block 32 under the bias of spring 60.

In the aforesigned locked-up position II of

web engaging shoes 42 the portion of plate 29 depending to the right hand side of shaft 12, as viewed in Fig. 4, is engaged with the hemispherically shaped upper end of a resiliently mounted stop pin 61 which is carried by channel bracket 31 and is depressed downwardly in such bracket to some extent. Bracket 31 is provided with aligned clearance openings in its upper and lower legs to accommodate pin 61. Adjacent its upper end pin 61 is provided with a flange 61a against which bears one end of a coiled compression spring 62 which is disposed about the shank of pin 61. At its other end spring 62 bears against a washer 63 disposed with a free fit about pin 61 and bearing against the upper leg of bracket 31. Adjacent its lower end, and below the lower leg of bracket 31, the shank of pin 61 is fitted with a washer and cotter key assembly to limit the upward movement of pin 61 in bracket 31. The relative positions of plate 29 (full lines) and pin 61 depicted in Fig. 4 is that assumed when active web engaging shoes 42 are bearing against the web W as depicted in Fig. 6.

While in connection with the foregoing description it was assumed that the web or webs handled by the web press were running in the plane depicted by the web W in Fig. 6, the paper break control device can be positioned so that the web engaging shoes 42 will bear against a single web, or a plurality of parallel running webs, which are running in virtually any other plane in the web press and afford the same kind of functioning in response to web breakage as hereinbefore described. As was pointed out in the foregoing, the assembly comprising stub shaft 34, bearing housing 15, shafts 12 and 13, and plate 20 may be positioned in any one of thirty-one different angularly spaced fixed positions in housing 14 and bearing bracket 16. To re-position the last mentioned assembly, it is only required that set screws 35 in sleeve 16b of bearing bracket 16 be loosened and the bolts 21 securing plate 20 to housing 14 be withdrawn, and such assembly then rotated in bearing bracket 16 and housing 14 to a new position where any two openings 20c disposed diametrically opposite the central axis of plate 29 align with threaded openings 14c in housing 14. If the presence of weight 57 on plate 55 were disregarded the last mentioned assembly could be secured in any one of thirty-six different angularly spaced fixed positions in bearing bracket 16 and housing 14. As will be appreciated, if the last mentioned assembly were positioned in another fixed position from that depicted, weight 57 would have to be correspondingly re-positioned on plate 55 to insure its proper counter-balancing action on shaft 12. As a practical matter therefore, the number of different positions that can be thus effected for the last mentioned assembly is thirty-one, corresponding to a total range of position change of 310°.

It should be understood that rotation of plate 29 in housing 14 a full 360° is not necessary to take care of all possible planes of web travel. If the possible range of 310° of position change is not sufficient, then the paper break control device can be reversed in its mountings on side frames 10 and 11 of the web press, from that shown in Fig. 1, so that housing 14 will be secured to side frame 10 and bearing bracket 16 will be secured to side frame 11.

We claim:

1. In a paper break control device for a print-

ing press or the like having spaced apart side frames and a web traveling therebetween, in combination, a control switch, an operating mechanism for said switch to be supported at opposite ends on the side frames of a press and comprising a rotatable shaft and an operating part for said switch carried on said shaft, said shaft being rotatable in one direction to one extreme position to operate said switch, and an assembly comprising an anti-friction bearing having an inner race non-rotatably supported on said shaft and having an outer race, a web engaging lever supported on the outer race of said bearing, means for biasing said lever into engagement with a traveling web and affording movement of said lever to a given extreme position upon breakage of the web and cooperating means on said inner and outer races of said bearing which upon the aforementioned movement of said lever effect rotation of said shaft to said one extreme position.

2. In a paper break control device for a printing press or the like having spaced apart side frames and a web traveling therebetween, in combination, a control switch, an operating mechanism for said switch to be supported at opposite ends on the side frames of a press and comprising a rotatable shaft and an operating part for said switch carried on said shaft, said shaft being rotatable in one direction to one extreme position to operate said switch, means normally biasing said shaft for rotation to an opposite extreme position, and an assembly comprising an anti-friction bearing having an inner race non-rotatably supported on said shaft and having an outer race, a web engaging lever supported on the outer race of said bearing, means for biasing said lever into engagement with a traveling web and affording movement of said lever to a given extreme position upon breakage of the web, and cooperating means on said inner and outer races of said bearing which upon the aforementioned movement of said lever effect rotation of said shaft to said one extreme position.

3. In a paper break control device for a printing press or the like having spaced apart side frames and a web traveling therebetween, in combination, a control switch, an operating mechanism for said switch to be supported at opposite ends on the side frames of a press and comprising a rotatable shaft and an operating part for said switch carried on said shaft, said shaft being rotatable in one direction to one extreme position to operate said switch, means normally biasing said shaft for rotation to an opposite extreme position, and an assembly comprising an anti-friction bearing having an inner race non-rotatably supported on said shaft and having an outer race, a web engaging lever supported on the outer race of said bearing, means for biasing said lever into engagement with a traveling web and affording movement of said lever to a given extreme position upon breakage of the web, and cooperating means on said inner and outer races of said bearing which upon the aforementioned movement of said lever effect rotation of said shaft to said one extreme position, the last mentioned means upon movement of said lever from its given extreme position being rendered ineffective to permit rotation of said shaft to its opposite extreme position by the first mentioned means.

4. In a paper break control device for a printing press or the like having spaced apart side frames and a web traveling therebetween, in

combination, a control switch, an operating mechanism for said switch to be supported at opposite ends on the side frames of a press and comprising a rotatable shaft and an operating part for said switch carried on said shaft, said shaft being rotatable in one direction to one extreme position to operate said switch, and an assembly comprising an anti-friction bearing having an inner race non-rotatably mounted on said shaft and having an outer race, a web engaging lever supported on the outer race of said bearing, spring means for biasing said lever into engagement with said web and affording movement of said lever to a given extreme position upon breakage of the web, an element fixed to the outer race of said bearing and an element fixed to the inner race of said bearing, the first mentioned element upon the aforementioned movement of said lever engaging with the last mentioned element to effect rotation of said shaft to said one extreme position.

5. In a paper break control device for printing presses or the like having spaced apart side frames and a traveling web therebetween, in combination, a control switch, an operating mechanism for said switch comprising a shaft rotatable in reverse directions, an operating part for said switch carried on said shaft, said shaft being rotatable in one direction to one extreme position to operate said switch and means affording rotatable bearing support for said shaft to be secured to the side frames of a press, a second shaft supported by said means in parallel and non-rotatable relation to the first mentioned shaft, and an assembly comprising an anti-friction bearing having inner and outer races, said shaft so that its inner race is non-rotatable but slide longitudinally thereon, a member slide longitudinally to different positions on said second shaft and straddling said bearing to effect corresponding positioning of the latter on said first mentioned shaft, means for adjustably securing said member on said second shaft, a web engaging lever supported on the outer race of said bearing, a spring for biasing said lever into engagement with a traveling web and affording movement of said lever to a given extreme position upon breakage of the web, an element fixed to the outer race of said bearing and an element fixed to the inner race of said bearing, the first mentioned element upon the aforementioned movement of said lever engaging with the last mentioned element to effect rotation of said shaft to said one extreme position.

6. The combination according to claim 5 wherein said member is provided with a releasable catch mounted thereon with which a part of the first mentioned element latches when said lever is moved a predetermined distance out of its given extreme position to provide for holding said lever out of working relation with a web.

7. The combination according to claim 5 wherein the first mentioned means further includes means affording positioning of said bearing supports, said shafts and said assembly, as a unit, in a plurality of angularly spaced fixed positions about an axis paralleling said shaft.

8. In a paper break control device for a printing press or the like having spaced apart side frames and a web traveling therebetween, in combination, a control switch, an operating mechanism for said switch to be supported at opposite ends on the side frames of a press and comprising a rotatable shaft and an operating

part for said switch carried on said shaft, said shaft being rotatable in one direction to one extreme position to operate said switch, and a plurality of like but independent assemblies, each of which comprises an anti-friction bearing having an inner race non-rotatably supported on said shaft and having an outer race, a web engaging lever supported on the outer race of said bearing, means for biasing said lever into engagement with a traveling web and affording movement of said lever to a given extreme position upon breakage of the web and cooperating means on the inner and outer races of said bearing which upon the aforementioned movement of its associated lever alone, while said shaft is out of said one extreme position, effect rotation of said shaft to said one extreme position.

9. In a paper break control device for a printing press or the like having spaced apart side frames and a web traveling therebetween, in combination, a control switch, an operating mechanism for said switch to be supported at opposite ends on the side frames of a press and comprising a rotatable shaft and an operating part for said switch carried on said shaft, said shaft being rotatable in one direction to one extreme position to operate said switch, means normally biasing said shaft for rotation to an opposite extreme position, and a plurality of like 25 part independent assemblies, each of which comprises an anti-friction bearing having an inner race non-rotatably supported on said shaft and having an outer race, a web engaging lever supported on the outer race of said bearing, means for biasing said lever into engagement with a traveling web and affording movement of said lever to a given extreme position upon breakage of the web and cooperating means on the inner and outer races of said bearing which upon the aforementioned movement of its associated lever alone while said shaft is out of said one extreme position, effect rotation of said shaft to said one extreme position, said first mentioned means being effective upon movement of all of the respective levers of said assemblies from their given extreme positions to rotate said shaft toward its opposite extreme position.

10. In a paper break control device for a printing press or the like having spaced apart side frames and a web traveling therebetween, in combination, a control switch, an operating mechanism for said switch to be supported at opposite ends on the side frames of a press and comprising a rotatable shaft and an operating part 55 for said switch carried on said shaft, said shaft being rotatable in one direction to one extreme position to operate said switch, and a plurality of like but independent assemblies each of which comprises an anti-friction bearing having an inner race non-rotatably mounted on said shaft and having an outer race, a web engaging lever supported on the outer race of said bearing, spring means for biasing said lever into engagement with said web and affording movement of said lever to a given extreme position upon breakage of the web, an element fixed to the outer race of said bearing and an element fixed to the inner race of said bearing, the first mentioned element upon the aforementioned movement of its associated lever engaging with the last mentioned element to alone, while said shaft is out of said one extreme position, effect rotation of said shaft to said one extreme position.

11. The combination according to claim 10 together with means to be secured to the side

11

frames of a press to afford rotational bearing support for said shaft, a second shaft supported by the last mentioned means in parallel and non-rotatable relation to the first mentioned shaft, and means comprising a part fixed on the first mentioned shaft, a lever, and a member fixed to said second shaft affording slidable bearing support for the last mentioned lever, said last mentioned lever being slidable to one extreme position to engage said part and effect rotation of said first mentioned shaft and said web engaging said levers to non-working positions, and said last mentioned lever when in said one extreme position being rotatable relative to the last mentioned member to releasably lock in said one extreme position.

12. The combination according to claim 10 together with means to be secured to the side frames of a press to afford rotational bearing support for said shaft, a second shaft supported by the last mentioned means in parallel and non-rotatable relation to the first mentioned shaft, like members included with each of said

5 independent assemblies, each of said members being slidable longitudinally on said second shaft and straddling an associated bearing to effect movement of the latter to corresponding positions on the first mentioned shaft.

13. The combination according to claim 11 wherein each of said members is provided with a releasable catch mounted thereon with which a part of an associated one of the first mentioned elements latches when its associated lever is moved a predetermined distance out of its given extreme position to provide for holding the latter out of working relation with a web.
